UNITED STATES PATENT OFFICE.

FRANK O. HARTMAN, OF MANSFIELD, OHIO, ASSIGNOR TO THE HARTMAN ELECTRICAL MANUFACTURING COMPANY, OF MANSFIELD, OHIO, A CORPORATION OF OHIO.

INDUCTANCE DEVICE.

Application filed July 8, 1925. Serial No. 42,275.

My invention relates broadly to electron tube amplification systems and more particularly to a coupling system for a plurality of electron tubes constituting an amplifier 5 and to the construction of coupling coils interlinking the several circuits of the electron tubes of the series.

One of the objects of my invention is to provide an electron tube amplification circuit arrangement wherein the magnetic coupling between the circuits of the coupling devices is confined to a small area and the circuit arranged in such manner that the lines of force may be effectively employed 10 within a concentrated area for transferring energy from one electron tube circuit to another with minimum loss.

Another object of my invention is to provide a series of coupling devices for interlinking the input and output circuits of 20 several electron tubes comprising an amplifier which will limit the magnetic fields emanating from the coupling coils to the coupling coils per se and substantially prevent the straying of magnetic lines from the coils which might otherwise tend to interlink other portions of the circuits of the 25 amplifier resulting in the production of undesired interfering currents.

Another object of my invention is to provide a construction of coupling device by 30 which energy may be transferred from one electron tube circuit to another in an amplification system with lower distributed capacity than is present in coils heretofore 35 available in the art, and with a concentrated magnetic field linking the windings of the coupling device for the efficient transfer of energy from one circuit to another.

Still another object of my invention is to provide a construction of coupling device arranged to produce a magnetic field concentrated within the coupling device to secure 40 the maximum transfer of energy from one circuit to another with minimum dielectric losses and with maximum separation of the high and low potential ends of the coils.

Still another object of my invention is to provide a self supporting coil structure so 45 wound that a magnetic field is produced which is substantially concentrated within the area of the winding for the reduction of stray magnetic lines of force and with the maximum separation of high and low potential points of the winding.

A further object of the invention is to provide a coupling system for interlinking the input and output circuits of an amplifier in which at least one of the coupling coils has an equal number of external fields of 60 substantially equal intensity which operate to substantially prevent coupling with other coupling systems in the amplifier.

A still further object of my invention is to provide a construction of self-supporting 65 inductance or transformer wherein the coil may be mechanically supported by means extending across a diametrical line thereof to rigidly position the turns of the coil in such manner that the physical size of the 70 winding may be concentrated within a small area with inherent advantages in the reduction in electrostatic capacity effects and the concentration of the magnetic field enclosed by the turns of the winding.

A still further object of my invention is to provide a self-supporting modified figure of 8 coil so latticed across its center that the center section does not build up to a height 75 of greater extent than the height of each lobe of the figure of 8.

A still further object of the invention is to provide an electron tube amplifier of great sensitivity having coupling coils interlinking the input and output circuits of the 80 several tubes in which the coupling coils are not susceptible to the radiation of signaling energy from nearby sources, such as local broadcasting stations, thereby eliminating inherent interference of signals in 85 the amplifier.

I have illustrated my invention with particular reference to radio frequency amplifiers for use in radio reception. Heretofore in the art it has been difficult to construct 90 radio frequency amplification systems which would be stable in operation and free from inherent oscillation. Various methods have been proposed for suppressing undesired oscillations in amplification systems all of 95 which have introduced complications in manufacture and have required the skillful balancing of the electron tube circuits for the prevention of the undesired oscillatory current in the amplification system. By my 100 present circuit arrangement I provide a structure of coupling device having its windings so arranged that they may be interposed between the input and output circuits of electron tubes connected in the tun- 110

ing circuit of a receiving system and by their inherent construction prevent the setting up of undesired oscillatory currents. I secure these results by constructing the 5 windings of the coupling devices in such manner that the fields thereof which may extend for any considerable distance from the coils or any stray magnetic lines of force which may exist about the coupling device 10 are opposed by substantially equal and opposite magnetic lines of force giving as a result a substantially nil coupling between the stray magnetic lines of force. The elimination of the magnetic coupling between 15 stray magnetic fields emanating from the coupling devices prevents the setting up of undesired oscillatory currents in the amplification system in so far as the magnetic coupling between the circuits is concerned. In 20 an amplification system the magnetic coupling between the several tube circuits is one of the important factors which tends to produce undesired oscillatory currents. The coupling coils are so constructed that they 25 have a north and south pole at the same end and if the north pole of one coil is tending to couple with the south pole of a second coil, the south pole of the first coil is tending to the same extent to couple with the 30 north pole of the second coil and these forces couple and oppose each other.

My invention will be more clearly understood from the specification hereinafter following by reference to the accompanying 25 drawings, wherein:

Figure 1 shows the application of the coupling devices of my invention to a radio frequency amplification system in a radio receiving apparatus; Fig. 1^a shows a modified 40 arrangement of the coupling system in which the primary and secondary windings are formed of inductively related figure of 8 windings; Fig. 2 is a theoretical view showing the method of winding the figure of 45 8 coupling inductances; Fig. 3 is a plan view illustrating the construction of the coupling inductances; Fig. 4 is a side elevation of the coupling inductances illustrated in Fig. 3; Fig. 5 is a detail view showing one of the 50 arrangements for supporting the turns of wire making up the inductances; Fig. 6 is an enlarged fragmentary view showing the central supporting web formed in the coil structure.

Referring to the drawings in detail, I have shown a radio receiving system for a radio frequency amplification circuit wherein the principles of my invention have been illustrated. Reference character 1 designates the receiving antenna system and reference character 2 shows a ground connection. In the antenna ground circuit I position one of the figure of 8 inductances designated by reference character 3 as having lobes 4 and 5 with a connection 6 from the

antenna 1 to a point along the lobes 4. The inductance 3 is tuned by means of variable condenser 7 which forms with the inductance a tuned input circuit for electron tube 8 comprising the first stage of radio frequency amplification. In the output circuit of the electron tube 8 the primary winding 9 of a coupling device 10 is positioned. A secondary winding 11 of the coupling device 10 is tuned by variable condenser 12 to the 70 frequency of the incoming signaling energy. The coupling device 10 may have its windings similarly constructed of figure of 8 coils as shown more clearly in Fig. 1^a or only one of the windings may be a figure 80 of 8 coil, while the other winding may be cylindrical or D-shaped as I have represented in dotted lines at 14 in Fig. 3. The windings may be built up with the same type of winding forming the figure of 8 85 coils illustrated in Fig. 1^a by continuing the structure of the windings which I have illustrated in Fig. 4, although such other secondary winding may be disconnected electrically from the cooperating winding. 90 With further reference to Fig. 1 of the drawings, the figure of 8 inductance tuned by variable condenser 12 forms the input circuit of electron tube 15, comprising a second stage of radio frequency amplification. The output circuit of the electron tube 15 is coupled with the input circuit of an electron tube 16, functioning as a rectifier by virtue of a coupling system 17. The coupling system 17 is similar to the coupling 95 system 10 in that it includes a primary winding 18 and a figure of 8 secondary winding 19 tuned by variable condenser 20. A grid leak and grid condenser 21 are connected in the input circuit of the detector tube 16. 100 The output circuit of the tube 16 includes primary winding 22 of audio frequency transformer 23, and the secondary winding 24 of transformer 23 delivers rectified energy to the audio frequency amplification tube 25. A suitable responsive device 26 is connected in the output circuit of the audio frequency amplifier. The anodes for each of the tubes are supplied from a source 27. The cathodes of the tubes are heated from 105 a source 28, the filament temperature of tubes 8 and 15 being controllable through rheostat 29, while the filament electrodes of tubes 16 and 25 are regulated through rheostat 30. The method of winding the figure 110 of 8 coils for eliminating stray magnetic fields and at the same time providing a self-supporting winding is clearly illustrated in connection with Fig. 2 of the drawings. In this diagram the inductance 11 has been illustrated as comprising a cylindrical portion 31 and a laterally extending diametrical portion 32. The turns of the inductance are supported upon themselves by weaving the 115 turns of the inductance along the lateral 120 portion 32. The turns of the inductance 125 are supported upon themselves by weaving the turns of the inductance along the lateral 130 portion 32.

portion 32. A set of five upstanding spokes or pins 33, 34, 35, 36, and 37 are temporarily provided and the inductance wound commencing for example as illustrated by arrow 5 38 and passing on the right hand side of spoke 33 over the left hand side of both spokes 34 and 35, between the spokes 35 and 36 and then tangentially along the right hand side of spokes 36 and 37 where the 10 winding passes around the left hand lobe in the direction illustrated at 39. At the top of the left hand lobe, the wire passes tangentially along the left hand side of spoke or pin 33 and between pins 33 and 34, 15 and then tangentially along the right hand sides of spokes 34 and 35 between spokes 35 and 36 and downwardly tangent to the left hand side of spokes 36 and 37 thence upwardly around the right hand lobe as 20 designated at 40. At the top of the right hand lobe the conductor passes tangentially to the left hand side of the spokes or pins 33 and 34 and between pins 34 and 35 in a downward direction tangent to the right 25 hand sides of spokes 35 and 36 passing between spokes 36 and 37 and upwardly at 41 around the left hand lobe. This winding again passes downwardly through the center passing along the right hand side of 30 spokes 33 and 34 between spokes 34 and 35 and down the left hand side of spokes 35 and 36 between spokes 36 and 37 and down the right hand side of spoke 37, and turns upwardly around the right hand lobe on 35 the line marked 56. The winding then again follows the path taken by conductor 38. In this manner the figure of 8 inductance has the magnetic field thereof concentrated in a small area and the winding is 40 self-supporting. The spokes or pins 33, 34, 35, 36, and 37 may be employed only during the manufacturing process, that is, during the winding operation and after the coil is wound the pins may be removed. By rea- 45 son of latticing the central portion of the coil in the manner described the turns at the center of the figure of 8 do not build up to a height greater than the height of the turns around each lobe of the coil. The 50 cylindrical portions of the turns 31 may be supported by means of the strips 42, 43, 44, 45, 46, 47, 48 and 49, which extend laterally along the coil 11 and may envelop both sides thereof. The strips are preferably of celluloid or insulating material which may have 55 the surface thereof softened in such manner that the turns 11 may be impressed into the surface of the material. I find that amyl-acetate is desirable for this purpose. 60 The surface of the celluloid is softened enabling the material to be pressed between the turns of the wire as represented more clearly in Fig. 5. The turns have been designated at 11 having insulating material 11^a there- 65 about. The celluloid material 45 has its sur-

face softened so that the material thereof may be pressed between the turns as indicated more clearly at 50.

As heretofore indicated the primary winding may be D-shaped as represented in Fig. 70 3 by reference character 14, the turns being supported by vertically extending strips 51, 52, 53, 54, and 55, similar to the vertically extending strips which support the secondary winding. 75

By virtue of the figure of 8 formation of the turns of the laterally extending woven form for the winding, the stray electromagnetic fields are substantially eliminated and the inductance arranged to be substantially 80 self-supporting facilitating the manufacture of the coupling devices. A portion of each turn is curved in a cylindrical formation while another portion lies in a serpentine path serving to mechanically support the 85 cylindrical portion of the winding and prevent the central portion building to a greater height than the circular portions.

While I have described my invention in certain particular embodiments, I desire that 90 it be understood that modifications may be made and that I intend no limitations upon the invention other than those imposed by the scope of the appended claims.

What I claim and desire to secure by Letters Patent of the United States is as follows:

1. An inductance device comprising in combination a winding having the contour 100 thereof substantially in cylindrical formation and formed with a serpentine web portion along a diametrical line of said cylindrical formation, the turns along said serpentine web portion serving to mechanically support the turns in said cylindrical formation in substantially parallel planes, and a plurality of strip members extending parallel to the axis of said cylindrical formation in which the turns are embedded for rigidly 105 bracing said inductance device. 110

2. An inductance device comprising in combination a substantially cylindrical coil having the turns thereof built one upon another, a web portion of said coil extending laterally across a diametrical line through 115 said cylindrical coil, the turns of said coil extending around the circumference thereof and laterally across said web portion in woven formation in planes substantially parallel with the planes containing the turns of said cylindrical coil, the turns within said web portion serving to mechanically support the turns of the said cylindrical coil in substantially parallel planes and strip members embedding the turns of said cylindrical coil, 120 said strip members extending parallel to the axis of said coil for rigidly bracing said inductance device.

3. An inductance device comprising in combination a winding having the turns 130

thereof wound in a modified figure of 8 shape with a pair of lobe portions on opposite sides of a diametrically extending web portion, said web portion being latticed a plurality of times across the center of said coil in a serpentine path limiting the height of the center portion substantially equal to the

height of each lobe portion and means embedding the turns of said lobe portions along lines parallel to the axis of said coil for increasing the rigidity of said inductance device. 10

FRANK O. HARTMAN.
